No. 832,668.

PATENTED OCT. 9, 1906.

R. HARTWIG.

GAS ENGINE.

APPLICATION FILED FEB. 25, 1904.

UNITED STATES PATENT OFFICE.

RUDOLF HARTWIG, OF RÜTTENSCHEID, NEAR ESSEN-ON-THE-RUHR,
GERMANY, ASSIGNOR TO FRIED. KRUPP AKTIENGESELLSCHAFT,
OF ESSEN-ON-THE-RUHR, GERMANY.

GAS-ENGINE.

No. 832,668.

Specification of Letters Patent. Patented Oct. 9, 1906.

Application filed February 26, 1904. Serial No. 195,289.

To all whom it may concern:

Be it known that I, RUDOLF HARTWIG, a subject of the German Emperor, and a resident of Rüttenscheid, near Essen-on-the-Ruhr, Germany, have invented certain new and useful Improvements in Gas-Engines, of which the following is a specification.

This invention particularly relates to the arrangement of the inlet and outlet valves for gas-engines.

Hitherto it has been usual to apply the inlet and outlet valves to the cylinder-covers or to the ends of the cylinders, putting the inlet-valve on top and the outlet-valve underneath. The disadvantage of this arrangement, however, is that the outlet-valves are with difficulty accessible, and in addition difficulties arise in the uniform cooling of the cylinder-covers or ends, and it not infrequently happens that they split, owing to unequal expansion.

Now this invention therefore is designed to provide a valve-gear which shall not possess the disadvantages above cited. The desired end is attained substantially by placing all the inlet and exhaust valves upon the back of the cylinder.

In the accompanying drawings is shown, by way of example, an application of the invention to the inlet and outlet valves of a double-acting four-stroke cycle-engine.

Figure 1 is a vertical longitudinal section through the cylinder and valve-chests, and Fig. 2 is a cross-section on the line 2 2 of Fig.

1. Fig. 3 is a section on the line 3 3 of Fig. 1. The working cylinder A, which is surrounded by the cylinder-jacket B, has at each end upon its back a flanged junction a'. Upon each of these junctions is mounted a valve-chest C of trough shape and having a corresponding junction C'. At the other end the chests are provided with ribs c², which bear against the ribs a² of the cylinder, but are not rigidly connected thereto, so that the chests C can expand freely relative to the cylinder during fluctuations of temperature. Above, the chests C are closed, with the exception of the openings for one inlet-valve D and one outlet-valve E. The valve-seats are placed in special boxes D' and E', secured to the chests C and carrying the unions and valve-gear. The cylinder-jacket B reaches to the valve-boxes D' E', and thus forms a space

which surrounds the chest C and in which the cooling-water can completely surround the chest C, so that no excessive rise of temperature need be feared at any point.

The above invention is obviously applicable to single-acting engines.

Having now particularly described and ascertained the nature of my said invention and in what manner the same is to be performed, I declare that what I claim is—

1. The combination with the cylinder and the water-jacket for the same, of a valve-chest supported on the cylinder to permit relative expansive movement between the chest and the cylinder and located within the water-jacket of the cylinder so that water in said jacket will directly surround and contact with the wall of the valve-chest.

2. The combination of the working cylinder having a flanged junction, a water-jacket surrounding the working cylinder and extending above the flanged junction, and a valve-chest spaced from the walls of and supported within the water-jacket and upon the flanged junction in such a manner as to permit relative expansive movement between the chest and the cylinder.

3. The combination of the working cylinder having a rib and a flanged junction, a water-jacket surrounding the working cylinder and extending above the flanged junction and the rib, and a valve-chest provided with a rib and a flanged junction supported respectively on the rib and the flanged junction of the working cylinder in such a manner as to permit relative expansive movement between the chest and the cylinder and located within but spaced from the walls of the water-jacket.

4. The combination with the cylinder, and the water-jacket, of a valve-chest having its walls of a single thickness, supported within the water-jacket upon the cylinder and spaced from all of the other walls of said jacket so as to be exposed to the water of the jacket on the outside of its walls.

The foregoing specification signed at Düsseldorf, Germany, this 26th day of January, 1904.

RUDOLF HARTWIG.

In presence of—

WILLIAM ESSENWEIN,
PETER LIEBER.
